CLAIM

The ornamental design for a shoe storage cabinet, as shown and described.

DESCRIPTION

FIG. 1 is a front perspective view of a shoe storage cabinet, showing my new design;

FIG. 2 is a rear perspective view thereof;

FIG. 3 is a front perspective view of the shoe storage cabinet in another angle;

FIG. 4 is a front elevational view thereof;

FIG. 5 is a rear elevational view thereof;

FIG. 6 is a left side view, the right side view being a mirror image of FIG. 6; and,

FIG. 7 is a top plan view thereof.

The broken lines in the figures depict portions of the shoe storage cabinet that form no part of the claimed design.

The dash-dot-dash lines are for an notating enlarged views; all broken lines form no part of the claim design.

1 Claim, 7 Drawing Sheets
